CLAIM

The ornamental design for a faucet handle hub, as shown and described.

DESCRIPTION

FIG. 1 is a front perspective view of the faucet handle hub showing my new design;

FIG. 2 is a rear perspective view thereof;

FIG. 3 is a right side elevational view thereof, the left side being a mirror image;

FIG. 4 is a top plan view thereof; and,

FIG. 5 is a bottom plan view thereof.

The broken line showing of the handle base, top and blade in FIG. 1 are for purposes of illustration only and form no part of the claimed design.
